Primary Examiner — Garth Rademaker*Assistant Examiner* — Katie S Mroczka(74) *Attorney, Agent, or Firm* — Cantor Colburn LLP**CLAIM**

We claim, the ornamental design for a confectionary strand, as shown and described.

DESCRIPTION

FIG. 1 is a perspective view of a confectionary strand, showing our new design in an exemplary embodiment;

FIG. 2 is a front elevation view of the embodiment shown in FIG. 1;
FIG. 3 is a back elevation view of the embodiment shown in FIG. 1;
FIG. 4 is a side elevation view of the embodiment shown in FIG. 1;
FIG. 5 is another side elevation view of the embodiment shown in FIG. 1;
FIG. 6 is a top plan view of the embodiment shown in FIG. 1;
FIG. 7 is a bottom plan view of the embodiment shown in FIG. 1;
FIG. 8 is a perspective view of a confectionary strand, showing our new design in another exemplary embodiment;
FIG. 9 is a front elevation view of the embodiment shown in FIG. 8;
FIG. 10 is a back elevation view of the embodiment shown in FIG. 8;
FIG. 11 is a side elevation view of the embodiment shown in FIG. 8;
FIG. 12 is another side elevation view of the embodiment shown in FIG. 8;
FIG. 13 is a top plan view of the embodiment shown in FIG. 8;
FIG. 14 is a bottom plan view of the embodiment shown in FIG. 8;
FIG. 15 is a perspective view of a confectionary strand, showing our new design in another exemplary embodiment;
FIG. 16 is a front elevation view of the embodiment shown in FIG. 15;
FIG. 17 is a back elevation view of the embodiment shown in FIG. 15;
FIG. 18 is a side elevation view of the embodiment shown in FIG. 15;
FIG. 19 is another side elevation view of the embodiment shown in FIG. 15;
FIG. 20 is a top plan view of the embodiment shown in FIG. 15;
FIG. 21 is a bottom plan view of the embodiment shown in FIG. 15;
FIG. 22 is a perspective view of a confectionary strand, showing our new design in another exemplary embodiment;
FIG. 23 is a front elevation view of the embodiment shown in FIG. 22;
FIG. 24 is a back elevation view of the embodiment shown in FIG. 22;
FIG. 25 is a side elevation view of the embodiment shown in FIG. 22;
FIG. 26 is another side elevation view of the embodiment shown in FIG. 22;
FIG. 27 is a top plan view of the embodiment shown in FIG. 22;
FIG. 28 is a bottom plan view of the embodiment shown in FIG. 22;
FIG. 29 is a perspective view of a confectionary strand, showing our new design in another exemplary embodiment;
FIG. 30 is a front elevation view of the embodiment shown in FIG. 29;

FIG. 31 is a back elevation view of the embodiment shown in FIG. 29;
FIG. 32 is a side elevation view of the embodiment shown in FIG. 29;
FIG. 33 is another side elevation view of the embodiment shown in FIG. 29;
FIG. 34 is a top plan view of the embodiment shown in FIG. 29;
FIG. 35 is a bottom plan view of the embodiment shown in FIG. 29;
FIG. 36 is a perspective view of a confectionary strand, showing our new design in another exemplary embodiment;
FIG. 37 is a front elevation view of the embodiment shown in FIG. 36;
FIG. 38 is a back elevation view of the embodiment shown in FIG. 36;
FIG. 39 is a side elevation view of the embodiment shown in FIG. 36;
FIG. 40 is another side elevation view of the embodiment shown in FIG. 36;
FIG. 41 is a top plan view of the embodiment shown in FIG. 36;
FIG. 42 is a bottom plan view of the embodiment shown in FIG. 36;
FIG. 43 is a perspective view of a confectionary strand, showing our new design in another exemplary embodiment;
FIG. 44 is a front elevation view of the embodiment shown in FIG. 43;
FIG. 45 is a back elevation view of the embodiment shown in FIG. 43;
FIG. 46 is a side elevation view of the embodiment shown in FIG. 43;
FIG. 47 is another side elevation view of the embodiment shown in FIG. 43;
FIG. 48 is a top plan view of the embodiment shown in FIG. 43;
FIG. 49 is a bottom plan view of the embodiment shown in FIG. 43;
FIG. 50 is a perspective view of a confectionary strand, showing our new design in another exemplary embodiment;
FIG. 51 is a front elevation view of the embodiment shown in FIG. 50;
FIG. 52 is a back elevation view of the embodiment shown in FIG. 50;
FIG. 53 is a side elevation view of the embodiment shown in FIG. 50;
FIG. 54 is another side elevation view of the embodiment shown in FIG. 50;
FIG. 55 is a top plan view of the embodiment shown in FIG. 50; and,
FIG. 56 is a bottom plan view of the embodiment shown in FIG. 50.
The broken lines in FIGS. 8-20, 22-26, 28, 36-48, 50-54 and 56 illustrate portions of the confectionary strand that form no part of the claimed design. The dash-dot-dash lines in FIGS. 8-12, 15-19, 22-26, 36-40, 43-47 and 50-54 represent the boundary of the claimed portions of the confectionary strand and form no part of the claimed design.
